(57) **CLAIM**

The ornamental design for a dispenser for liquid soap, as shown and described.

DESCRIPTION

FIG. 1 is a perspective view of a dispenser for liquid soap, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof; and,

FIG. 9 is a perspective view showing the dispenser for liquid soap taken from a lower side.
The broken lines shown in the figures illustrate environmental or other features that form no part of the claimed design.
